HAND MIRROR MOUNT

Joseph Casalino, Forest Hills Gardens, Long Island, N. Y., assignor to Dieplast Corporation, New York, N. Y., a corporation of New York

Application December 5, 1944, Serial No. 566,661

5 Claims. (Cl. 88—102)

1

This invention relates to a hand mirror mount of the kind comprising essentially a handle portion and a frame portion enclosing the mirror unit, that is to say, the mirror and its backing.

The primary object of the invention is a mirror mount of this type which can be readily molded of plastic material and the parts of which can be molded, without undue complication of the dies, in two self-locking pieces. Other objects and advantages will be apparent from the ensuing description and accompanying drawing.

In the drawing, Fig. 1 is a broken-off, elevational view, partially sectioned and illustrating a preferred embodiment; Fig. 2 is a section on the line II—II of Fig. 1; Fig. 3 is a section on the line III—III of Fig. 1; and Fig. 4 is a broken-out sectional view illustrating a modification.

One of the elements or parts of the mount consists of a substantially T-shaped handle, generally designated 1, including the hand-grip portion 2 and a cross-piece 3. At its outer ends the cross-piece is formed with the enlargements 4 through which apertures 5 extend in the general direction of the axis of the handle 2. A channel 6 is formed in the upper edge of the cross-piece 3 and extends upwardly at its outer ends, opening through the upper surface of the enlargements 4.

The other element of the mount consists of an open frame 7 having an inwardly directed channel 8 of similar contour to the channel 6 in the cross-piece 3. On each of the free ends of the arms of the frame 7 there is formed an extension 9 of a reduced section from that of the adjacent portion of the frame proper so as to provide shoulders 10 for abutment with the upper surfaces of enlargements 4 when the extensions 9 are entered into the apertures 5.

The free spacing of the ends of the arms of the frame 8 is different from the spacing of the apertures 5. By "free spacing" is meant the distance between the arms of the frame as it comes from the dies. As will be understood, however, the arms of such a frame can be flexed or sprung toward or away from each other and hence the extensions 9 may readily be entered into the apertures 5. In this instance the free spacing of the arms of the frame is somewhat greater than the spacing of the apertures 5, so that the arms are flexed toward one another to be entered into the apertures.

As shown in Figs. 1 and 2, the apertures 5 are substantially larger throughout, in the direction of the median plane of the frame, than the ex-

2

tensions 9, with the result that when the frame has been set into the handle and released, the extensions 9 are resiliently held in close engagement with the outer walls of apertures 5. This result is utilized to achieve a snap interlock between appropriately formed portions of the frame and handle.

As shown in Fig. 1, the lower end of each extension 9 protrudes through and beyond its aperture 5 and is formed with a lateral projection 11 which engages beneath the adjacent corner of enlargement 4, thereby securely interlocking the frame and handle. When the elements are assembled, as described, a continuous, inwardly directed mirror unit channel is provided by the channels 6 and 8 in the handle and frame respectively and by means of the described snap interlock the mirror unit is securely held in place. If a more permanent bond between the handle and frame is desired, it can readily be achieved by inserting and cementing a wedge piece in the indicated clearance between each extension 9 and the wall of aperture 5 from which it is slightly spaced.

25 In the modified form illustrated in Fig. 4, the handle and frame are designated 12 and 13, respectively. Except as below described, these elements may be precisely of the form of those of Figs. 1 to 3. In this instance the free spacing of 30 the arms of frame 13 is less than that of the spacing of the handle cross-piece apertures, of which one marked 14 is shown in Fig. 4; with the result that when the frame extension 15 is flexed and entered into aperture 14 and then released, 35 it engages the inner rather than the outer wall of aperture 14, the frame as a whole thereby tending to maintain a somewhat tighter grip on the mirror unit.

Also, in this form, the frame extension 15 terminates substantially flush with the adjacent surfaces of the handle 12 and the snap interlock between the frame and handle is effected by means of an inwardly directed projection 16 on the extension 15 engaging a shoulder 17 formed 45 in one wall of the aperture 14.

In the light of the foregoing description, the following is claimed:

1. A two-piece, self-locking, molded plastic hand-mirror mount comprising a substantially 50 T-shaped handle incorporating a channel extending along the upper edge of the cross-piece thereof and having at each end of the cross-piece an aperture extending entirely through the same in the general direction of the longitudinal axis of the handle, a resilient, open frame hav-

ing an inwardly directed channel of similar form to the cross-piece channel, extensions on the free ends of the frame of a length to extend through said apertures and of a reduced section from that of the frame proper, thereby forming frame shoulders for abutment with the handle section adjacent such apertures, the said apertures being substantially larger throughout their length than the said extensions in the direction of the median plane of the frame, and a locking projection on the end of each said extension, the free spacing of said extensions being different from the spacing of said apertures and thereby adapting the said projections to snap-interlock with the handle section when the frame section is flexed and the extensions thereof thrust into said apertures, the ends of said channels being thereupon adapted to register and form a continuous, inwardly directed mirror-unit channel.

2. A two-piece, self-locking, molded plastic hand-mirror mount comprising a substantially T-shaped handle incorporating a channel extending along the upper edge of the cross-piece thereof, said cross-piece having at each end thereof an aperture extending in the general direction of the longitudinal axis of the handle and a lateral recess enlargement in one of the aperture walls, a resilient, open frame having an inwardly directed channel of similar form to the cross-piece channel, extensions on the free ends of the frame of a length to extend through said apertures and of a reduced section from that of the frame proper, thereby forming frame shoulders for abutment with the handle section adjacent such apertures, the said apertures being substantially larger throughout their length than the said extensions in the direction of the median plane of the frame, the free spacing of said extensions being different from the spacing of said apertures and thereby requiring said frame to be flexed to enter the extensions in the apertures, and a lateral locking projection on each of said extensions located and adapted for snap-engagement with said recess enlargements when the extensions are thrust into the apertures, the ends of said channels being thereupon adapted to register and form a continuous, inwardly directed mirror-unit channel.

3. A two-piece, self-locking, molded plastic hand-mirror mount comprising a handle having at the inner end thereof two, spaced apertures extending in the general direction of the longitudinal axis of the handle, a resilient, open frame, extensions on the free ends of the frame adapted for entry into said apertures and of a reduced section from that of the frame proper, the said apertures being substantially larger than the said extensions to permit lateral movement of the extensions therein, the free spacing of said extensions being different from the spacing of said apertures and thereby requiring said frame to be flexed to enter the extensions in the apertures, and snap-interlock means on said extensions and handle located and adapted for engagement by the resiliency of the frame.

4. A two-piece, self-locking, molded plastic hand-mirror mount comprising a handle having at the inner end thereof two, spaced apertures extending in the general direction of the longitudinal axis of the handle, a resilient, open frame having its ends shaped and dimensioned for entry into said apertures, the latter being substantially larger than the said ends to permit lateral movement of such ends therein, the free spacing of such ends being different from the spacing of said apertures and thereby requiring said frame to be flexed to enter its ends into the apertures, and snap-interlock means on said handle and ends of the frame.

5. A two-piece, molded plastic hand-mirror mount comprising a handle having at the inner end thereof two, spaced apertures extending in the general direction of the longitudinal axis of the handle, a resilient, open frame having its ends shaped and dimensioned for entry into said apertures, the latter being substantially larger than the said ends to permit lateral movement of such ends therein, the free spacing of such ends being different from the spacing of said apertures and thereby requiring said frame to be flexed to enter its ends into the apertures, and means for securing said frame ends against withdrawal from the apertures.

JOSEPH CASALINO.
